G. H. LELAND,
PROCESS OF MAKING GOLD CROWNS,
APPLICATION FILED FEB. 2, 1917.

1,257,367.

Patented Feb. 26, 1918.

Inventor:

George Henry Leland.

By Louis W. Schmitz, Atty.

UNITED STATES PATENT OFFICE.

GEORGE HENRY LELAND, OF HARTFORD, CONNECTICUT.

PROCESS OF MAKING GOLD CROWNS.

1,257,367.

Specification of Letters Patent.

Patented Feb. 26, 1918.

Application filed February 2, 1917. Serial No. 146,234.

To all whom it may concern:

Be it known that I, GEORGE HENRY LELAND, a citizen of the United States, residing at Hartford, in the county of Hartford and State of Connecticut, have invented 5 certain new and useful Improvements in Processes of Making Gold Crowns, of which the following is a specification.

My invention relates to improvements in 10 processes of making gold crowns, and the object of my improvement is to produce a process of making gold crowns for dental use involving the reproduction of a die of steel in a casting of soft metal by the use 15 of a mold in which such reproduction is effected by means of a special mold of flexible rubber and which mold is adapted for repeated use.

In the accompanying drawing:—

20 Figure 1 is a front elevation of the cast form of soft metal made by my improved process and a finished gold crown mounted thereon.

Fig. 2 is a plan view of the same.

25 Fig. 3 is a front elevation, on an enlarged scale of the upper part of the form shown in Fig. 1, the outline of the crown being shown in dotted lines.

Fig. 4 is a side elevation of the same.

30 Fig. 5 is a front elevation of the blank for the crown, the upper portion being in part broken away.

Fig. 6 is a plan view of the flask for forming the mold of rubber.

35 Fig. 7 is a sectional view of the flask, the steel die in position therein, and the means for supporting the steel die.

Fig. 8 is a similar view after the rubber has been poured into the flask.

40 Fig. 9 is a similar view of the rubber mold after the metal for the cast form has been poured therein.

Fig. 10 is a view part in section and part in side elevation of the mold.

45 Fig. 11 is a similar view of the flask and other parts shown in Fig. 9.

In the use of my process I make use of a die 10 of steel of the special form from 50 which a copy or reproduction is made of a cast form 11 of soft metal, having a low fusing point, that is used in shaping the gold crown 13 and by my invention I produce a special mold 12 for use in casting the said cast form 11, which mold 12 I produce of soft, flexible rubber, whereby the same is 55 adapted for repeated use.

The die 10 comprises an elongated structure having the die proper 14 at one end that is formed to correspond approximately to that desired for the finished crown 13, having an enlarged base portion 15 at the other end that may be provided with a screw threaded hole 16 for a screw 20 for connecting with a supporting device, which may be in the form of a strip 21 of metal, and intermediate the said ends has a generally tapered shank portion 17, the said die 10 being used as a pattern for casting the cast form 11 in the mold 12. The supporting strip 21 is narrower than the opening in the flask 18.

The flask 18 consists of an open cup, having a cylindrical side wall 19, that is of slightly greater depth on the inner side than the die 10 or the portion thereof that it may be desired to reproduce.

In use, the die 10 is inserted into the flask 18 and then the mold 12 is formed around the same by pouring into the flask 18 the necessary amount of the proper composition 80 to form the mold 12 of soft rubber, after which the rubber mold 12 is vulcanized. Then the die 10 and the mold 12 are removed from the flask 18 and the mold 12 is slipped off from the die 10, and the mold 12 is ready 85 for use.

In such use, the mold 12 is dusted on the interior with powdered soap stone to provide a lining and then the molten soft metal is poured therein to produce the cast 90 form 11.

As first produced the crown receiving end 22 of the form 11 is an accurate reproduction of the die proper 14, and before using this for shaping the crown 13, the same is 95 in most cases modified by cutting away or carving to produce such varied and special form as may be desired for the particular form of the crown.

The blank 23 for the crown 13 is initially 100 in the form of a cap with cylindrical side walls and plain closure for the end, and the same is forced onto the end 22 and changed in form so as to produce the desired final shape for the finished crown 13.

105 A plurality of dies, in some cases as many as twenty-five of different shape, may be mounted on a single support arranged as a set, and by providing a corresponding number of flasks, a plurality of molds may be 110 produced at one operation.

The molds are thus produced in sets and

are provided with suitable markings for identification.

Thus the same set of dies is used for producing sets of molds in quantities.

5 The process of forming the molds is a factory process, the molds being available for general distribution to different users.

As mentioned, a set of dies may involve as many as twenty-five of different shape, 10 and a set of molds would include a corresponding number.

The user would be provided with the set of molds only, and would make his selection of the individual mold in a particular case 15 by the use of implements for determining the size of the tooth and the crown, such as the dentimeter and the shell-gage. Thus from measurements of the size of the tooth there would be selected a blank for a crown 20 and also a mold that would be most nearly like the finished crown desired, so that a minimum of working over of the soft metal casing would be required to obtain the desired finished form.

25 Thus means are provided for obtaining a satisfactory and superior operative result with a minimum of operative detail and in a minimum of time, involving a quick and good result.

30 I claim as my invention:—

1. The process of shaping gold crowns from cup-shaped blanks comprising providing a metal die of elongated form having at one end a crown portion of arbitrary form, 35 forming a mold of soft, flexible rubber around the said die, producing a metal reproduction of the said die by casting in the said mold, operating on the said reproduction by cutting away material thereof so as to produce a modified crown portion to correspond to the shape desired for the finished crown, and swaging a blank for the crown on the said modified crown portion.

2. The system of shaping gold crowns 45 from cup-shaped blanks comprising providing a set of metal dies having crown portions at one end of different and arbitrary form, selecting from the said set an individual die having a crown portion approximating that desired for the finished crown,

forming a mold of soft, flexible rubber around the said individual die, making a reproduction of the said individual die of metal by casting in the said mold, operating on the said reproduction by cutting away 55 material thereof so as to produce a modified crown portion to correspond to the shape desired for the finished crown, and swaging a blank for the crown on the said modified crown portion.

3. The method of shaping gold crowns from cup-shaped blanks, comprising providing a set of molds of soft rubber composed of individual molds having casting openings of different and arbitrary form, the said casting 65 openings each having the inner end closed and having the inner end portion shaped to correspond approximately to the shape of a tooth crown, providing a blank for a crown, selecting a mold having the inner end portion of the casting opening corresponding approximately in size to the size of the said blank, casting a soft metal form in the said mold, operating on the crown end portion of the said form by cutting away material to produce a modified crown end portion to suit the individual to be fitted, and shaping the said blank on the said modified crown end portion.

4. The method of shaping gold crowns 70 from cup-shaped blanks, comprising providing a mold of soft rubber having a casting opening and which opening is closed at the inner end and has a crown portion adjacent the said inner end shaped to correspond approximately to the shape of a tooth crown, 75 providing a blank for a crown, casting a soft metal form in the said mold, so as to reproduce the said crown portion at one end of the said form, operating on the said crown portion of the form by cutting away material to produce a modified crown portion 80 suitably to provide individuality thereto, and shaping the said blank on the said modified crown portion.

GEORGE HENRY LEILAND.
